ATTORNEY

UNITED STATES PATENT OFFICE.

ALFRED J. TRIGWELL, OF SAN JOSE, CALIFORNIA.

BATTERY-PLATE.

1,367,288.

Specification of Letters Patent.

Patented Feb. 1, 1921.

Application filed April 16, 1920. Serial No. 374,465.

To all whom it may concern:

Be it known that I, ALFRED J. TRIGWELL, a subject of the King of Great Britain, and a resident of San Jose, in the county of 5 Santa Clara and State of California, have invented certain new and useful Improvements in Battery-Plates, of which the following is a specification.

The grid of a battery plate is subject to 10 varying degrees of temperature when in use which causes alternate expansion and contraction of its several parts. This expansion and contraction causes the loosening of the filling material, parts of which fall down 15 between adjacent plates, thereby necessitating the use of separators to prevent short circuiting of the said plates and reducing their efficiency and shortening the life of the same. Furthermore, as now constructed, 20 the strain to which the sides of the grid, or the frame, are subjected frequently results in their complete rupture.

It is the object of the present invention to provide a grid so formed and constructed 25 as to permit the proper expansion and contraction of the grid frame and the cell walls therein without rupturing any part of the grid. A further object is to provide a structure that can expand and contract without 30 dislocating the filling material.

In the drawing:

Figure 1 is a side elevation of a battery plate embodying my invention.

Fig. 2 is an enlarged section on 2—2 of 35 Fig. 1 as formed ready to be filled.

Fig. 3 is an enlarged section on 2—2 of Fig. 1 after filling and after the forming is completed.

Referring more particularly to the drawing, 1 indicates the frame portion of a battery plate grid, the same usually being made of lead and of suitable proportions. At one or more points, preferably at the corners of the frame, the same is formed into loops as 45 at 2, the said loops curving outwardly in the embodiment shown. The frame 1 and the intersecting cell walls 3 are formed inte-

grally with retaining flanges 4 encompassing the opening of each cell on one side of the plate as shown.

The opening to each cell on the opposite side of the plate is full size but the depth of each cell is somewhat greater than the desired depth of the finished plate, the excess of cell wall being cut or slit as at 5. After 50 the filling material has been placed in position these cell walls are bent inwardly as shown at 6 to form flanges corresponding to flanges 4 so that the material in each cell is securely held in position and cannot be dislodged except by its entire disintegration.

It may now be seen that any unusual strain on frame 1 due to the alternate heating and cooling of the plate is readily taken up by the loops 2, and any distortion of the 65 cells in the plate through the alternate expansion and contraction of the cell walls, does not materially affect the filling in the cells or the operation thereof since the flanges 4 and 6 effectually hold the material 70 in position. While loop 2 may be located in any desired position the corner is deemed best since in that position it readily allows for the expansion and contraction of two sides. It is to be understood that in using 75 the term "loop" in the following claims any formation is included in which an excessive length is provided in the frame without increasing its principal proportions.

It is further understood that changes in 80 form and construction may be made within the scope of the appended claims.

I claim:

1. A battery plate having an expansion loop formed in the frame thereof.

2. A battery grid having an expansion loop formed in two of the opposite corners thereof.

3. A battery plate comprising a grid having an expansion loop formed in the frame 90 thereof and having means formed integrally therewith to prevent the dislocation of filling material from the cells thereof.

ALFRED J. TRIGWELL.
